US00D918947S

(12) **United States Design Patent** (10) Patent No.: **US D918,947 S**
(45) Date of Patent: **** May 11, 2021**

(54) **DISPLAY SCREEN OR PORTION THEREOF
WITH GRAPHICAL USER INTERFACE**

(71) Applicant: **Lutron Technology Company LLC**,
Coopersburg, PA (US)

(72) Inventors: **Rhythm Agarwal**, Bethlehem, PA (US);
Benjamin F. Bard, Zionsville, PA (US); **Erica L. Clymer**, Northampton, PA (US); **Jemma C. Robinson**, Brooklyn, NY (US); **Sara M. Thompson**, Brooklyn, NY (US); **Shenchi Tian**, Easton, PA (US)

(73) Assignee: **Lutron Technology Company LLC**,
Coopersburg, PA (US)

(**) Term: **15 Years**

(21) Appl. No.: **29/689,303**

(22) Filed: **Apr. 29, 2019**

Related U.S. Application Data

(63) Continuation of application No. 29/612,902, filed on Aug. 4, 2017, now Pat. No. Des. 847,174.

(51) **LOC (13) Cl. 14-04**

(52) **U.S. Cl.**

USPC **D14/486**

(57)

CLAIM

The ornamental design for a display screen or portion thereof with graphical user interface, as shown and described.

DESCRIPTION

The sole FIGURE shows a display screen or portion thereof with graphical user interface showing our new design. Shading represents tonal contrast.

The peripheral dashed broken lines illustrate a display screen or portion thereof, and form no part of the claimed design.

1 Claim, 1 Drawing Sheet
